UNITED STATES PATENT OFFICE

2,491,187

TOILET SEAT PROTECTOR

Martin Knoetzschi, Guatemala City,
Guatemala

Application February 26, 1947, Serial No. 730,929

3 Claims. (Cl. 4—247)

1

This invention relates to toilet seat protectors and more particularly to a device for automatically providing U-shaped toilet seats with sanitary coverings.

Devices of this character which cover the entire toilet seat with a unitary web of paper automatically replaced by a fresh covering after each use, are wasteful of paper and hence expensive in operation. In addition unless some means is provided to dispose of the soiled paper after each use, the device would be extremely unsanitary.

It is among the objects of this invention to provide a device for covering a U-shaped toilet seat with strips of paper that afford complete protection against soiling of the seat and consequent infection of the user, that will automatically change the covering after each use and will dispose of the soiled paper without the necessity for handling thereof, and that is economical in operation, simple to use and not likely to get out of order.

According to the invention, the device comprises three separate covering units, one for each side of a hinged or pivoted U-shaped toilet seat and one for the cross piece or back thereof connecting the sides, each covering unit being associated with paper cutting mechanism and all three units, together with their respective cutting mechanism being jointly controlled by the pivotal movement of the seat. The covering units each carry a roll of paper which is automatically unrolled by means of feed rollers so as to move a fresh surface on the top of the seat after each use when the seat is pivoted upwards, while the used portion of the paper is automatically cut off and dropped into the bowl when the seat is pivoted downward to the position of use.

In the accompanying drawings in which is shown one of various possible embodiments of the several features of the invention,

Fig. 1 is a plan view of the device,

Fig. 2 is a sectional view taken along line 2—2 of Fig. 1,

Figs. 3 to 5 are detailed views of the paper cutting mechanism, and

Figs. 6 to 8 are detailed side views of the device showing the paper cutting mechanism in various stages of operation.

Referring now to the drawings, a substantially U-shaped seat 1 is provided having a pair of levers 2, each of which is affixed at one end on the cross piece or back 11 of the seat. Levers 2 each have a transverse bearing openings 3 therein, by means of which levers 2 and seat 1 can be pivoted

2

on a fixed rod 4 mounted in upright standards 5 and 6 affixed to the floor and straddling the seat. The free ends of the levers are each provided with an adjustable weight 8 which automatically pivots seat 1 about rod 4 to retain the seat in a substantially vertical position when not in use.

Riding over the sides 9 and 10 of seat 1 and the back 11 thereof are strips of covering paper 12, 13 and 14 which are fed from covering units 11, 12 and 13, respectively. As the essential parts of each of the covering units are alike, only one of the units will be described in detail, while the others will be described only to the extent necessary for a clear understanding of the operation of the device.

As shown in Figs. 1 and 2, affixed beneath side 9 of seat 1 and depending therefrom is a pair of spaced brackets 9' and 10'. Idly mounted on a shaft 15 journaled at each end in one of said brackets is a roller 15 carrying a roll of paper. The strip of paper 12 from said roll is placed on the surface of side 9 of seat 1 and then passed around said side so as to be positioned between feed rollers 17 and 18, rotatably mounted on shafts 33 and 18' respectively, journaled in bearing openings in brackets 9' and 10'. To insure gripping of the strip of paper for proper feed thereof the surface of each of the feed rollers is preferably provided with a rubber facing, while supply roller 15 is preferably slightly braked by any conventional means to keep the strip of paper 12 always in taut condition.

In order that the paper be unrolled from each of the rollers 15, it is necessary that one of the feed rollers be driven. In the embodiment shown herein, roller 17 is rotated by the mechanism hereinafter described.

Affixed beneath the back 11 of seat 1 and depending therefrom is a pair of spaced parallel brackets 26 and 27. Journaled in each of said brackets and extending therefrom on both sides thereof, is a horizontal drive shaft 22 having bevel gears 28, 29 thereon, near each end thereof, which mesh with a corresponding bevel gear 30, 31 respectively at the ends of shafts 32, 33, the latter each carrying a driven feed roller 17 under each of the sides 9 and 10 of the seat.

A gear 21 is idly mounted on shaft 22 so as to engage the teeth of an internal gear segment 1 unitary with a vertical supporting arm 70 affixed to rod 4 at one end thereof in juxtaposition to upright standard 5. Gear 21 has helical teeth 71 on one side thereof and is urged by a spring 24, surrounding shaft 22 between gear

21 and an adjusting wing nut 23, against the corresponding helical teeth 72 of a coupling member 25, rigidly affixed on shaft 22. By this arrangement when seat 1 is pivoted upwardly around rod 4 by the weights 8, gear 21 rolls over the toothed internal gear segment 7, rotating in a counter-clockwise direction, as seen in Figs. 6 to 8, and the helical teeth 71 thereon mesh with the helical teeth 72 of coupling member 25 acting as a driving clutch to rotate shaft 22, whereas during the downward motion of seat 1, gear 21 will rotate in a clockwise direction and the helical teeth 71 thereon will ratchet over the helical teeth 72 on the coupling member 25 and not transmit motion to shaft 22.

As shaft 22 also carries a driven feed roller 17 thereon which supplies paper to back 11 of the seat, it is apparent that each upward motion of seat 1 will rotate shaft 22 and effect the simultaneous rotation of the three driven feed rollers 17, thereby unrolling the strips of paper from rollers 15 and replacing the used paper on the sides and back of the seat.

The paper strips 12, 13 and 14 which pass between the feed rollers 17 and 18 are guided thereby so as to be moved over and beyond a cutting bar 19 with which a pair of cutting knives 20 and 34 cooperate to shear the strip. Cutting knives 20 and 34 are each pivotally mounted at one end as at 35 and 36 and provided at their free ends with pins 37 and 38 respectively, which are pivoted in longitudinal slots 57', 58' in arms 59 for actuation of the cutting knives 20 and 34 under the sides 9 and 10 of the seat and in longitudinal slots 57, 58 in arm 56 for actuation of the cutting knives under the back 11 of the seat.

Movement of actuating arms 59 and actuating arm 56 only occurs during the downward motion of seat 1 and will pivot cutting knives 20 and 34 about their pivots 35 and 36 respectively in the direction of the arrows, as shown in Figs. 3 and 4, to effect cutting of the paper strips. The mechanism for moving actuating arm 59 and actuating arm 56 comprises a lever 39 which is firmly affixed to seat 1 and is pivotally mounted on rod 4 in juxtaposition to standard 6 by means of bearing opening 40 in said lever. Lever 39 has a laterally extending arm 41 which engages from below the end 42 of a lever 43 rotatably mounted on a stud 44 extending laterally outward from upright standard 6. Arm 41 of lever 39 is in engagement with end 42 of lever 43 when seat 1 is in an approximately vertical position, as shown in Fig. 6, and lever 43 is thereupon driven when lever 39 is pivoted, due to the turning down of the seat. The driving of lever 43 is, however, restricted to only a portion of the travel of lever 39, for as levers 39 and 43 are pivoted about different axes, i. e., rod 4 and stud 44 respectively, end 41 of lever 39 will cease to engage and drive end 42 of lever 43 after lever 39 has pivoted a short distance.

Pivotally mounted on shaft 22 as at 22' is a U-shaped member 45' having a lever arm 45 extending from one of the arms thereof. Moving of lever 43 by lever 39 causes the laterally extending arm 41 of lever 43 to engage the end 48 of lever arm 45 of member 45' and pivot the latter downward about shaft 22. Lever 45 transmits the motion imparted to it by lever 43 to its rear portion 46 extending parallel to rod 4, to two additional levers 49 pivotally mounted on studs 50 extending laterally outward from brackets 26 and 27. The levers 49 each have a reduced portion 51 at the rear end thereof which fits into a slot

52 on rear portion 46 of U-shaped member 45', as shown in Figs. 1, 4 and 5. Pivoting of member 45' as heretofore described, will also pivot levers 49 about their respective studs 50. Each of the 10 front ends 53 of levers 49 has a yoke 54 into each of which projects a pin 55 extending longitudinally from each end of actuating arm 56, which will be reciprocated up and down by the pivoting of levers 49. Reciprocation of actuating arm 56 will pivot cutting knives 20 and 34 downwardly about their pivots 35 and 36 into engagement with the companion cutting bar 19 and thereby shear the paper strip 14. To insure perfect separation of the strip cutting knives 20 and 34 overlap at their free ends when pivoted to cutting position.

The apparatus for cutting the paper strips on the sides of the seat is similar to the one described for the back 11 thereof, with the difference, however, that the actuating arm 56 is replaced by an actuating arm 59, as shown in Figs. 1 and 3, which in the embodiment herein consists of a separate arm affixed to member 45' on the left side of the seat as at 46', while member 45' is extended on the right side of the seat to form actuating arm 59.

After end 42 of lever 43 is no longer engaged and driven by end 41 of lever 39 as above described, as shown in Fig. 8, lever 43 will swing back to its initial position in response to the urging of a spring 60'.

Simultaneously when end 48 of lever arm 45 of U-shaped member 45' which is engaged by arm 47 of lever 43 is released, which occurs when lever 43 swings back to its original position under the urging of spring 60' as heretofore described, spring 61' will pivot U-shaped member 45' and hence actuating arms 59 and actuating arm 56 with their cutters 20 and 34 to their original position as shown in Fig. 8.

In order that the cutting mechanism operate only during the downward motion of the seat, the laterally extending arm 41 of lever 39 must be guided under the end 42 of lever 43 as the seat pivots upwardly under the urging of weights 8. For this purpose arm 41 is provided with a dovetailed projection 60 unitary therewith and extending longitudinally therefrom, which is slidably seated in a corresponding dovetailed 50 groove at the end of lever 39. A spring 61 affixed at one end to lever 39 and at its other end to dovetailed projection 60, draws laterally extending arm 41 in the direction indicated by the arrow in Fig. 8. When seat 1 is pivoted upwardly, arm 55 41 which has been displaced from the end of lever 39 by spring 61 will be cammed away from the end 42 of lever 43, whereas during downward motion of seat 1, arm 41 of lever 39 will bear against end 42 of lever 43, as shown in Fig. 6, and thereby move lever 43 into operative position.

It can thus be seen that fresh strips of paper will be placed on the sides 9 and 10 and back 11 of the seat when the weights 8 pivot the seat to vertical position and the used portions of the strips will be cut off during the downward motion of the seat, to drop into the bowl.

As many changes could be made in the above construction and many apparently widely different embodiments of this invention could be made without departing from the scope of the claims, it is intended that all matter contained in the above description or shown in the accompanying drawing, be interpreted as illustrative and not 70 75 in a limiting sense.

Having thus described my invention, what I claim as new and desire to secure by Letters Patent of the United States is:

1. A device for providing U-shaped toilet seats with paper coverings, said device comprising means for pivoting said seat from horizontal to vertical position, said means comprising a pair of upright standards, a horizontal rod affixed in the upper ends of said standard and parallel to the rear of said seat, a pair of spaced levers pivoted on said rod and affixed at one end to said seat and a weight at the free end of each of said levers normally to pivot said seat to vertical position, a paper supply roll under each of the sides and back of said seat, a pair of feed rollers in juxtaposition to each of said supply rolls, cutting means interposed between each of said supply rolls and its respective pair of feed rollers, a transmission actuated by the pivoting of said seat about said rod to actuate said feed rollers and a transmission actuated by the pivoting of said seat about said rod to actuate said cutting means, said feed rollers being actuated by the pivoting of said seat from horizontal to vertical position and said cutting means being actuated by the pivoting of said seat from vertical to horizontal position, the transmission to actuate said feed rollers comprising a drive shaft rotatably mounted beneath the back of said seat, a feed roller shaft under each of the sides of said seat, gear means on said drive shaft and said feed roller shafts operatively to connect said drive shaft to said feed roller shafts, a gear idly mounted on said drive shaft having helical teeth on one face thereof extending laterally therefrom, a coupling member rigidly affixed to said drive shaft in juxtaposition to said gear and having helical teeth extending laterally therefrom, an internal gear segment rigidly affixed to said rod at one end thereof and meshing with said drive shaft gear teeth and a spring urging said gear into engagement with said coupling member, the helical teeth on said gear engaging the helical teeth on said coupling member and rotating said drive shaft when said seat is pivoted from horizontal to vertical position and ratcheting over said helical teeth on said coupling member when said seat is pivoted from vertical to horizontal position.

2. A device for applying paper coverings to a pivoted U-shaped toilet seat, said device compris-

ing means for pivoting said seat from horizontal to vertical position, a paper supply roll under each of the sides and the back of said seat, a pair of paper feed rollers in juxtaposition to each of said supply rolls, cutting means interposed between each of said supply rolls and its respective pair of feed rollers, a transmission actuated by the pivoting of said seat from horizontal to vertical position for actuating said feed rollers to feed fresh paper from said supply rolls and a transmission actuated by the pivoting of said seat from vertical to horizontal position for actuating said cutting means to cut off the used portions of said paper.

15 3. A device for providing U-shaped toilet seats with paper covering, said device comprising a pair of upright standards, a horizontal rod affixed in the upper ends of said standards and parallel to the rear of said seat, a pair of spaced levers pivoted on said rod and affixed at one end to said seat, a weight on the free end of each of said levers normally to pivot said seat to vertical position, a paper supply roll under each of the sides and back of said seat, a pair of feed rollers in juxtaposition to each of said supply rolls, cutting means interposed between each of said supply rolls and its respective pair of feed rollers, said cutting means comprising a cutting bar affixed beneath each of the sides and back of said seat and extending longitudinally thereof and a pair of cutting knives each pivoted at one end to an end of said cutting bar, and a transmission actuated by the pivoting of said seat about said rod to actuate said feed rollers and a transmission actuated by the pivoting of said seat about said rod to actuate said cutting means, said transmission for actuating said cutting means being operatively connected to the free ends of said cutting knives to reciprocate the latter about said pivots.
